UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A KNIFE-BLADE.

SPECIFICATION forming part of Design No. 22,482, dated May 30, 1893.

Application filed April 26, 1893. Serial No. 471,981. Term of patent 7 years.

To all whom it may concern:

Be it known that I, CHARLES F. SMITH, a citizen of the United States, residing at New Britain, in the county of Hartford and State of Connecticut, have invented and produced a new and original Design for a Knife-Blade, of which the following is a specification, reference being had to the accompanying drawing, forming part thereof, in which the only figure is a side elevation of a knife-blade showing my design.

The general contour of the blade is somewhat in the form of a cimeter, but the tip of the blade is rounded and curves to a point *a*,

a little back of the extreme end of the tip at 15 the junction of the end and back *b*. The bolster *c* at the butt end of the blade is in about the middle of its width and the blade has rounded corners *d d* on each side of the bolster as shown. 20

What I claim is—

The design for a knife blade, substantially as herein shown and described.

CHARLES F. SMITH.
